UNITED STATES PATENT OFFICE.

JOHN NILSON, OF OTTAWA, KANSAS.

WRENCH MECHANISM.

1,366,587.

Specification of Letters Patent. Patented Jan. 25, 1921.

Application filed May 11, 1920. Serial No. 330,585.

To all whom it may concern:

Be it known that I, JOHN NILSON, a citizen of the United States of America, residing at Ottawa, in the county of Franklin 5 and State of Kansas, have invented certain new and useful Improvements in Wrench Mechanism, of which the following is a specification.

The primary object of the invention relates in the provision of a wrench mechanism for applying resiliently mounted bolts to the overlapped flanges of a railway scarf joint, wherein the bolt is held under the tension of a spring during rotation thereof to a locked position for co-operation with the rail webs.

With this general object in view, the invention consists of the novel combination and arrangement of parts hereinafter more fully described in connection with the accompanying drawing, and in which like reference characters designate corresponding parts throughout the several views.

In the drawing,

Figure 1 is a vertical transverse sectional view of a rail joint scarf with the bolt operating tool shown partly in section.

Fig. 2 is a view similar to Fig. 1 with the bolt released, and

Fig. 3 shows the bolt in side elevations.

My invention contemplates the overlapping of adjacent end portions of railway rails such as 10 and 11, the webs 12 of the rails having thickened end portions 13 with complementally formed cut-away portions 14 in the adjacent sides thereof and with the adjacent base flanges correspondingly cut-away as at 15.

The ends of the rails are readily overlapped as herein illustrated, it being understood that the tread of each rail is cut-away similarly to the base flange thereof whereby a substantially unbroken tread or ball is provided for the track throughout the joint. The base of the rail is also uniform throughout the joint so that a substantially smooth bottom surface is provided for the connected rails accommodating the track for use upon concrete ties as it is not material that my form of joint be positioned over a tie as required in the ordinary rail joint construction.

The adjacent faces of the overlapping web portions 13 are complementally formed with longitudinal grooves 16 in the face of one web portion and longitudinal ribs 17

upon the face of the other web portion adapted for slidable reception within said grooves 16. Oblong perforations 18 provided longitudinally through the web portions 13 are adapted for passing the oval-shaped heads 19 of bolts 20 therethrough. The bolts 20 have squared blocks 21 in the form of heads at the ends thereof opposite the oval heads 19 and it will be apparent that the bolts 20 are readily passed through the perforations 18 upon grasping the blocks 21.

A helical spring 22 surrounds each bolt 20 adjacent its block 21 and upon forcing the block 21 toward the adjacent web 15, compressing the spring 22, the oval head 19 of said bolt is forced outwardly of diametrically opposite lugs 23 upon the outer face of the opposite rail web so that upon turning the bolt 20 a quarter revolution and then releasing the bolt, the oval head 19 thereof will seat between opposite pairs of the said lugs 23 as shown in Figs. 1 and 2 of the drawing. It will be understood that when the bolt 20 is in its locked position, the oval head 19 thereof is at right angles to the perforations 18 through which the bolt extends but upon turning the bolt so that the head 19 is in alignment with the perforations 18, the bolt is readily withdrawn for releasing the joint.

An operating tool for applying and removing the bolts 20 comprises a head 24 having a socket 25 for fitting over the head 21 of the bolt, the head 24 being journaled adjacent one end of a lever 26 having a latch 27 for hooking over the opposite side of the joint when the wrench is positioned for use. A similar lever 28 attached to the wrench head 24 turns the bolt when the lever 26 has projected the bolt through the perforations 18 sufficiently to permit the oval head 19 of the bolt to clear the lugs 23. The operation of securing my joint easily and quickly by means of the wrench operating as described upon the bolts 20 will be fully understood as well as the manner of releasing and removing the bolt 20 from the perforations 18 whereby the rails 10 and 11 are disconnected.

The springs 22 upon the bolt 20 provide a slightly resilient joint connection between the rails while the ribs 17 within the grooves 16 hold the rails in proper alignment. The entire rails have substantially a uniform amount of material throughout their entire

length so that the strength of the track is not appreciably diminished when my form of resilient scarf is employed. This form of scarf and resilient connection forms a 5 serviceable track structure for employment upon any form of railroad with or without ties such as wood, metal or concrete ties. While the form of the invention herein set forth is believed preferable, it will be 10 understood that changes may be made therein without departing from the spirit and scope of my invention.

What is claimed as new is:

15 A device for applying resilient bolt members to rail joints having overlapping web

portions comprising a body adapted for receiving the head of the bolt for turning, an operating lever for said body, a compression lever journaled upon said body and projecting above the tread of the track when 20 in use, and a hook swingingly carried by said compression lever adapted for engagement over the tread of the rail above the plane of the bolt being operated upon whereby the bolt may be shifted longitudinally 25 and revolved during the operation of the device.

In testimony whereof I affix my signature.

JOHN NELSON.
